UNITED STATES PATENT OFFICE.

JOSEPH SUTTON, OF WALLA WALLA, WASHINGTON.

TWINE CUTTER.

1,407,446.

Specification of Letters Patent. Patented Feb. 21, 1922.

Application filed April 18, 1921. Serial No. 462,310.

To all whom it may concern:

Be it known that I, JOSEPH SUTTON, a citizen of the United States, residing at Walla Walla, in the county of Walla Walla and State of Washington, have invented certain new and useful Improvements in Twine Cutters, of which the following is a specification.

This invention relates to devices for cutting twine and has for its object to provide a means for cutting twine that is sufficiently light in weight to be conveniently carried on the finger and when placed thereon is readily accessible for operation.

15 A further object is to provide a means for cutting twine that is cheap to manufacture, that is ornamental, and upon which may be placed advertising matter.

20 A further object is to provide a means for cutting twine that is a time saver and a twine saver.

A further object is to provide a means for cutting twine that is operable in close quarters, as in opening packages.

25 A further object is to provide a means for cutting twine that will eliminate twine cuts on the hands and by means of its large shoulders is easy on the finger.

A further object is to provide a means 30 for cutting twine in which the cutting members may be easily removed for sharpening or renewal purposes.

A further object is to provide a means 35 for cutting twine, having cutting members so designed that by grinding in the simplest manner the most efficient cutting means is obtained.

With these and other objects in view reference is now had to the accompanying 40 drawings in which—

Fig. 1 is a perspective view of the device.

Fig. 2 is a side elevation of the knife blade.

45 Fig. 3 is a side elevation of the slotted cutting blade.

Fig. 4 is a front elevation of the cutting member assembled.

Having reference to the drawings, like 50 numerals refer to like parts throughout, and the numeral 1 refers to a ring which may be of any suitable material, which may be finished elaborately, and may be of various sizes to accommodate the finger of the 55 operator.

The ring is provided with enlarged

shoulders 2 to give ample bearing on the finger to insure ease and comfort and upon these shoulders may be placed advertising matter if desired.

Extending radially from the ring and positioned intermediate of the shoulders is a mounting 3 having a groove 4 extending lengthwise thereof and in which is secured the cutting members, consisting of a slotted 60 blade 5 having the upper edge of the slot ground on one side only, a second slotted blade 6 which is similarly ground with the difference that in one the grinding occurs on the opposite side of this upper edge; i. e., 65 one may be a left and the other a right hand blade. This method of grinding has a twofold object in that with a slotted member a single grind from one side is a more simple method of sharpening the blade than 70 grinding both sides, which is due particularly to the slotted feature; and by this method of grinding cutting edges are obtained that may be placed on the outside 75 of the cutting member, which upon trial 80 gives the maximum of efficiency.

The slotted blades are so designed that a substantial base 7 is provided which when properly seated in the groove 4 tends to maintain maximum rigidity.

85 A knife blade 8 has its upper edge 9 doubly ground to provide a cutting edge which may be placed centrally between the outer slotted blades.

The cutting edge 10 of the slotted blades 90 is tapered upward while the cutting edge 11 of the knife blade is tapered downward and the blades are so designed that the edges form a cutting juncture with one another by two of the edges being above and one 95 below each other; hence with the blades so positioned and ground as above mentioned a cutting member is provided having two upper cutting edges formed on the outer side of the cutting member, and a single cutting 100 edge placed intermediate of said two upper cutting edges.

The blades are provided with apertures 12 which register with one another, and a screw or bolt 13 passes through the mounting, in threaded engagement therewith, and through these apertures to hold the blades rigidly and removably within the slot 4 of the mounting 3.

110 It is now obvious that by removing the screw 13 the blades may be removed for sharpening purposes, and also they may be

removed for renewal or to substitute blades forming a larger jaw 14 for cutting heavier twine, such as binder twine or the like.

In use the ring is placed upon the finger 5 with the jaw preferably pointed outward when the device is ready for operation; then the twine to be cut is drawn between the cutting edges of the cutting member and the twine is severed.

10 Having thus described my invention, I claim—

1. In a twine cutter, the combination of a finger ring, cutting blades mountable in said ring, said cutting blades consisting of 15 a pair of slotted blades sharpened on the upper side of said slot and having the cutting edges on the outer side thereof, a knife blade disposed between said slotted blades and tapered to form a cutting juncture with

said slotted blades, and a means for rigidly 20 and removably attaching said blades to said ring.

2. In a twine cutter the combination of a finger ring, a slotted mounting extending radially from said ring, broad shoulders on 25 said ring, a three bladed cutting means, each of said blades having a cutting edge and having the cutting edges position with two above and one below each other, the outer of said blades having a single ground edge 30 with the edge formed on the outer side, the lower blade having a double ground edge and positioned beneath and between the upper blades, and a means for rigidly attaching said cutting means in said slotted 35 mounting.

In testimony whereof I affix my signature.
JOSEPH SUTTON.
